Primary Examiner — Kendra Leslie Hamilton

CLAIM

The ornamental design for a teething toy, as shown and described.

DESCRIPTION

FIG. 1 is a front perspective view of a teething toy, showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a rear perspective view thereof.

In the drawings, the equal-length broken lines depict portions of the teething toy that form no part of the claimed design.

1 Claim, 8 Drawing Sheets
